(57) **CLAIM**

The ornamental design for a display screen or portion thereof with animated graphical user interface, as shown and described.

DESCRIPTION

FIG. 1 is a front view of a display screen or portion thereof with animated graphical user interface, showing a first image of a sequence;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof; and,

FIG. 8 is a front view of an eighth image thereof.

FIGS. 1-8 depict a sequence of images for a display screen or portion thereof with animated graphical interface showing our new design. The appearance of the transitional image sequentially transitions between the images of the sequences shown in FIGS. 1-8. This process or period in which one image transitions to another forms no part of the claimed design. The broken lines in FIGS. 1-8 show the display screen or portion thereof and elements of the graphical user interface that are environmental aspects and form no part of the claimed design.
